APPARATUS FOR DELIVERING CHARGES
OF MATERIALArthur D. Smith, Spokane, Wash., assignor to
Aluminum Company of America, Pittsburgh,
Pa., a corporation of Pennsylvania

Application November 25, 1944, Serial No. 565,141

1 Claim. (Cl. 214—29)

1

This invention relates to apparatus for delivery of charges of material into receptacles, such as the melting chambers of scrap furnaces.

The object of the invention is to provide a charging mechanism which will be compact and strong in construction and simple in operation, receiving the material and delivering successive charges into the furnace or other receptacle.

A further object of the invention is to provide such apparatus adapted to deliver the charges of material from opposite ends so as to selectively supply the charges to receiving structures on opposite sides of a central area, such as the charging sides of two adjacent furnaces.

Further objects of the invention, particularly in the provision of a balanced structure carrying its driving and operating mechanism for movement as a unit along a track will appear from the following description taken in connection with the accompanying drawings, in which

Fig. 1 is a plan view of the machine in position to charge a furnace at the right;

Fig. 2 is a side elevation of the machine shown in Fig. 1;

Fig. 3 is a vertical sectional view longitudinally through the center of the charging trough;

Fig. 4 is a transverse sectional view taken on the line IV—IV of Fig. 2;

Fig. 5 is an end elevation looking from the right of Fig. 2;

Fig. 6 is a sectional view taken on the line VI—VI of Fig. 2; and

Fig. 7 is a vertical sectional view on enlarged scale on the line VII—VII of Fig. 2.

The entire charging mechanism is supported on frame F mounted on wheels 12 running on a pair of rails T which extend between the charging sides of two adjacent furnaces A and B. It is held in place in front of either furnace by means of anchor pins P dropped into the holes in brackets K in front of the furnace doors and passing through matching holes in bracket plates E protruding laterally from the ends of frame F.

Material is gathered in containers such as "tote" boxes X (Fig. 4) and hauled to the machine by platform trucks which place the box X against the tilting table H as shown with the bottom edge 40 of the box in the hooks 41 at the lower edge of the tilting table. The operator locks the box X to the tilting table H with the toggle hooks 42 (Fig. 7), these hooks being operated by cranks 43 and shaft 44 through the toggle mechanism 45. Counterclockwise movement of the cranks 43 draws the hooks 42 down against stop shoulder 46 and locks them there.

2

The table H is mounted on a shaft 50 by brackets 47 (Figs. 4 and 5) and is rigidly fastened to gear segment 48 by member 49, said shaft 50 being mounted at its ends in blocks 51 adjustably mounted in cradles 52 on cross beams 17 and 18 (Figs. 1 and 2) of the frame F. A motor 55 through shaft 56 and gearing 57 mounted on cross beams 33 drives pinion 58 meshing with the teeth 59 of gear segment 48 to rotate this segment and lift the table H and box X upward (broken lines in Fig. 4) to a position approximately 30° above the horizontal, thereby allowing the scrap in box X to discharge between guides 60 and across the end 61 of the table H into a horizontal charging trough 28 from which the scrap is slid into the furnace opening at either end of the trough. The operator may level out the load in the trough by any suitable means, such as a rake, and when the trough is filled, the motor drive 55 is oppositely rotated to partially lower the table H to a position where the remaining scrap in the box X will be held against sliding out.

With the trough 28 loaded the furnace door is opened and the charge of scrap is engaged by the pusher plate 62 which is moved toward the furnace, the trough and scrap moving with it until as the end 31 of the trough reaches within the furnace opening 32 of furnace A the spring stop 63 (Fig. 3) engages plate 64 of the frame F sharply stopping the trough movement and permitting continued movement of the pusher plate and scrap to project the latter into the furnace. Reversing the pusher drive will lead the pusher 62 and trough 28 back into position with spring stop 65 against plate 66 for refilling by again lifting table H, the furnace door being closed between successive charges emptying the scrap from box X into furnace A. After a load of scrap is charged into one furnace the anchor pins P may be removed and a sling hooked between the pusher and the opposite furnace B so that drive of the pusher toward A will draw the machine along tracks T to furnace B. After anchoring the machine by pins P to brackets K of furnace B, the pusher 62 may be positioned at the opposite end of the trough 28 and swung through 180°, thereby conditioning it for feeding the scrap over trough end 30 into furnace B.

The frame support and operating mechanism are of strong rugged construction mounting all the machinery on the base formed by the cross bars 10 supported by the longitudinal beams 11 carrying at their ends the journals 13 on shafts 14 of wheels 12. Vertical struts 15, 16 carry the upper cross beams 17, 18 bearing the longitudinal

channels 21 from which cross channels 20 depend and the brackets 19 carrying shafts 24 of flanged rollers 25 supporting the trough structure 28 for longitudinal movement. At each end of the frame F inclined struts 35 extend from cross beams 10 below to the outer ends of side beams 21 above to support these ends connected by the channel irons 36 and having side plates 37 and the bracket plates E.

The trough 28 comprises a bottom piece 26, vertical side pieces 29 and corner angles 27 resting on the rollers 25. The trough sides 29 carry angle bars 71 forming channels for the rollers 72 of the pusher assembly including plate 62. The pusher carriage comprises side plates 73 carried by rollers 72 and in turn supporting the pusher head 74 by top strips 75 on each side. Attached to the head 74 by shaft 76 are pusher arms 77 connected at their ends to pusher plate 62 resting on the bottom plate 26 of the trough 28. The arms 77 and plate 62 may be swung through 180° to either right or left position as indicated in Fig. 3.

To drive the pusher a motor 80 through shaft 81, gears 82 (on platform 23) and transverse shaft 83 drives the sprocket 84 engaging a chain 85 on each side of the trough supporting structure. Each chain 85 passes around pulleys 86 at each end of the machine and adjustably mounted sprockets 87 at the center and the ends of the chains are fastened at 88 to the side extensions 89 of the pusher assembly. Motor 80 through chains 85 moves the pusher and trough forward to charge the furnace and on reversal pulls the trough out of the furnace by engagement of the wheels 72 of the pusher carriage with the end stops 10.

The double ended delivery employs the same trough and pusher for supplies to opposite furnaces without turning around the machine as a whole. It is simply run from one furnace to the other along trackway T, charging one while the other is heating the melt.

The indirect moving of the trough by the engagement of the pusher with the charge utilizes a single drive for the pusher and trough and at the same time permits the pusher to move independently of the trough when the latter is stopped by engagement of its spring stops 63, 65 with plates 64, 66, respectively. The jar of this sharp stoppage also frees the load of scrap from the trough due in part to the momentum of the charge and the pusher behind it, so that the scrap is projected into the furnace.

The lifting table H at the side is positioned close to the adjacent track support and its overhanging load is counter balanced by the heavy framework and equipment positioned over near the other track. The table in lifting also turns around a center between the tracks and any over-balancing effect is at a maximum at or near the start of the lifting. Therefore, any load that

can be started can be safely carried over to the trough because the tipping force of the load decreases as the lifting progresses.

After the box X of scrap is positioned on the lifting table the workman has only to control the table and pusher drives in proper sequence leveling off the load if the scrap rolls into the trough unequally. The charging action after the furnace doors are opened is a prompt direct projecting of the load into the melting chamber, after which the doors are closed during re-loading of the trough. Successive charges from the box X are thus rapidly thrown into the furnace and the empty box returned by reversal of the lifting table H and release of the gripping hooks.

While the machine has been described in connection with the charging of scrap into furnaces, it is not limited to such material or operation, and its principle applies to the delivery of charges of other materials for other purposes within the combinations set forth in the appended claim.

I claim:

25 In a material charging device, in combination, a support adapted for translation between two opposite charging points, a material receiving trough carried by said support for free movement therealong in opposite directions toward each of said points, a carriage mounted for movement in opposite directions longitudinally of said trough toward and away from each of said charging points, means for effecting said movement of said carriage and a pusher element 30 shaped to operate in said trough, said element being fixed to said carriage and adapted to contact and shift material held in said trough as the carriage is moved toward either charging point and comprising a member swingably mounted on said carriage to be moved into operative position in either direction depending upon the direction of movement of the carriage.

A. DEAN SMITH.
